UNITED STATES PATENT OFFICE.

BENJAMIN BROIDO, OF NEW YORK, N. Y., ASSIGNOR TO THE SUPERHEATER COMPANY, OF NEW YORK, N. Y., A CORPORATION OF DELAWARE.

SUPERHEAT REGULATOR.

Original application filed April 10, 1918, Serial No. 227,803. Divided and this application filed December 18, 1920. Serial No. 431,608.

To all whom it may concern:

Be it known that I, BENJAMIN BROIDO, a citizen of the United States, and resident of New York, N. Y., have invented certain new and useful Improvements in Superheat Regulators, of which the following is a specification.

My invention has reference to so-called regulators, the function of which is to reduce the amount of superheat that has been imparted to steam in the superheater after its generation in the boiler. It has for its object the provision of improved apparatus for controlling the amount of heat abstracted from the superheated steam by the regulator.

This application is a division of my application, Serial Number 227,803, filed April 10, 1918.

20 In the drawings filed herewith and forming part hereof, Fig. 1 shows my invention in place in connection with a water tube boiler of a well-known type; Fig. 2 shows a sectional view, on an enlarged scale, on line 2—2 of Fig. 1; Fig. 3 is a sectional view, on a still larger scale, on line 3—3 of Fig. 2; Fig. 4 illustrates on a still larger scale a valve and its controlling element used in my invention.

30 Throughout the views portions have been broken away and sectioned where this conduced to clearness.

The boiler, composed of upper drum 1, lower drum 2, and tubes 3 connecting them, 35 is enclosed in the housing 4. Gases on their way from furnace 5 to stack connection 6 are guided in their passage over the tubes 3 by the baffles 7. Water is fed to the boiler by pipe 8, and steam leaves the upper drum 40 by steam pipe 9. This pipe conveys it to the header 10 of the superheater, whence it flows by the pipes 11 to the superheater elements 12, which extend into the spaces between the rows of tubes 3. Here it is superheated by the gases, and then returns by 45 way of the pipes 13 to header 14, which it leaves by pipe 15.

As far as described the apparatus is well known. A description of my improvement 50 will now be given.

Instead of taking the steam from header 14 directly to the engine, or other point of use, I first carry it to and through a regu-

lator, when its temperature is regulated as will be described farther on. This idea in 55 itself is not new, but the arrangement of my regulator, and the means I use for obtaining an amount of regulation varying as desired are novel as far as I am aware.

The regulator itself, designated by reference numeral 16, is placed in the proximity of the upper drum 1, and at a little distance above the water level, indicated by dotted line *a*.

The regulator comprises the cylindrical 65 shell 17, provided at each end with a flange 18, to which are bolted the flanges 19—19 of the headers 20—20. Between each flange 18 and its connected flange 19 there is clamped a tube sheet 21. Tubes 22 extend 70 between these two tube sheets and have their ends rolled into or otherwise secured to them.

Steam pipe 15 is connected to the left hand header 20, and from the right one leads 75 the steam pipe 15^a.

At its lowest point the regulator drum 17 is connected by pipe 23 with the water space of the boiler. Pipe 23 is provided with the normally open valve 24. The highest point 80 of drum 17 is connected by means of pipe 25 with the steam main 15^a. This pipe 25 is provided with the normally open valve 26, with the special valve 27, and with the thermostatically controlled valve 28. The 85 valve 27 permits steam flow from the regulator drum 17 to the main 15^a, but will not permit water to flow through it.

Its construction will be readily understood 90 from Fig. 3. Its casing 29 is closed at the top by cover 30, through which extends the opening 31 communicating with pipe 25. The lower end of opening 31 is provided with the seat 32, in the shape of a spherical segment. A ball 33 of the same radius as 95 the seat 32 is placed within the casing. At some distance from the top of the casing, sufficient to give the ball 33 some play, is the perforated plate 34, supported on lugs 35. The bottom of the casing is provided 100 with an opening 36 communicating with a length of the pipe 25.

The ball 33 is of material light enough to float on water, but heavy enough to sink in steam of the pressure and temperature used, 105 and of course capable of resisting the condi-

tions of temperature, moisture, and pressure involved.

The valve 28 and its co-operating thermostatic element 38 are illustrated on an enlarged scale in Fig. 4. The spring 51 tends to keep the balanced valve 50 in housing 37 closed, this tendency being opposed by pressure exerted by the fluid in chamber 52 actuating the valve through rod 53. The pressure in chamber 52 varies with the amount of fluid forced into the chamber, or allowed to leave the chamber, through pipe 39, the other end of which communicates with chamber 54. Fluid is forced from the chamber 54 or allowed to enter it through pipe 39 in response to a rise or a drop respectively of the temperature of element 38. The valve and its control are of a known commercial type and it is not thought necessary to enter further into any detailed description of its construction, as its precise form is not a part of my invention. Its action is such that when the temperature of the steam in pipe 15^a falls below a certain point, the valve is closed; when said temperature rises above a certain higher point, the valve is wide open; while at intermediate temperatures the valve assumes corresponding intermediate positions. Any thermostatically controlled valve answering these requirements and otherwise suitable may be substituted for the one shown and described.

The highest point of pipe 25 is at a considerable elevation, the exact distance depending on circumstances, as will be explained below.

The action of the apparatus is as follows. The steam on its passage from pipe 9 through the superheater to pipe 15 inevitably experiences a pressure drop, so that the pressure on the surface *a* in the drum 1 exceeds slightly that within steam pipe 15^a and within casing 17 of the regulator.

This difference in pressure forces water up through pipe 23 into the regulator casing 17. The difference in pressure is slight, but is sufficient to raise the water high enough to fill casing 17. To guard against water passing over into the main by means of pipe 25, the double precaution is taken of elevating the highest point of pipe 25 sufficiently so the difference in pressure is insufficient to raise water to this highest point; and in addition there is put into this pipe 25 the valve 27, which, as explained above, closes the moment the water fills it.

From this explanation it will be clear that casing 17 will always tend to be filled with water. The heating and vaporizing of this water will lower the temperature of the steam flowing through tubes 22, the steam generated in the casing 17 passing through 25 into main 15^a and tending farther to reduce the temperature of the steam in the main. When the steam temperature in 15^a

is at such a point, that the valve 28 is partly closed and prevents the free passage of steam through pipe 25; a certain amount of back pressure builds up, with the result that the water level in casing 17 falls. The amount which this level is depressed evidently depends upon the extent to which the passage of steam through 25 is throttled by valve 28. This valve 28 is so adjusted, as already briefly stated above, that it is wide open at all steam temperatures above a predetermined point, so that the regulator may have the maximum possible effect. Below such point it gradually closes with a drop in temperature. When it is entirely closed, the regulator drum will evidently remain filled only with steam which will assume the same temperature as that flowing through the tubes 22, and no farther regulating effect occurs.

What I claim is:

1. In apparatus of the class described, and in combination, a boiler, a superheater, a regulator of the type in which the temperature of the superheated steam flowing through it is lowered by water not in direct contact with it by an amount depending on the amount of water in the regulator, a conduit from the boiler to the superheater, a second conduit from the superheater to the regulator, a third conduit carrying steam from the regulator, the regulator being placed above the water level of the boiler, a pipe connecting a low point of the regulator water space with the boiler water space, a pipe connecting a high point of the water space with one of the said conduits communicating with the regulator and two valves in said last named pipe the first adjacent to the regulator and permitting flow of steam but not of water from the regulator to the conduit and the other operative responsively to the temperature of the steam in the conduit assuming a closed position when the steam temperature falls below a predetermined point, an entirely open position a second higher predetermined point, and intermediate positions for intermediate points, said last named pipe extending to a considerable elevation above the regulator.

2. In apparatus of the class described, and in combination, a boiler, a superheater, a regulator of the type in which the temperature of superheated steam flowing through it is lowered by water not in direct contact with it by an amount depending upon the amount of water in the regulator, a conduit from the boiler to the superheater, a second conduit from the superheater to the regulator, a third conduit carrying steam from the regulator, the regulator being placed above the water level of the boiler, a pipe connecting a low point of the regulator water space with the boiler water space and a pipe connecting a high point of the water

space with one of the said conduits communicating with the regulator.

3. In apparatus of the class described, and in combination, a boiler, a superheater, a regulator of the type in which the temperature of the superheated steam flowing through it is lowered by water not in direct contact with it by an amount depending upon the amount of water in the regulator, the regulator being placed above the water level of the boiler, means to conduct the steam from the boiler through the superheater and thereupon through the regulator, means actuated by the pressure difference caused by the pressure loss in the superheater to force boiler water into the regulator water space, and means operative responsive to the temperature of the super-

heated steam to control the amount of water forced into the regulator.

4. In apparatus of the class described, and in combination, a boiler, a superheater, a regulator of the type in which the temperature of the superheated steam flowing through it is lowered by water not in direct contact with it by an amount depending upon the amount of water in the regulator, the regulator being placed above the water level of the boiler, means to conduct the steam from the boiler through the superheater and thereupon through the regulator, and means actuated by the pressure difference caused by the pressure loss in the superheater to force boiler water into the regulator water space.

BENJAMIN BRODO.
